UNITED STATES PATENT OFFICE

170,011

HOT AIR FURNACE

Raymond R. Dupler, Toledo, Ohio

Application November 3, 1952, Serial No. 22,112

Term of patent 14 years

(Cl. D81—1)

To all whom it may concern:

Be it known that I, Raymond R. Dupler, a citizen of the United States and a resident of Toledo, Lucas County, Ohio, have invented a new, original, and ornamental Design for a Hot Air Furnace, of which the following is a specification, reference being had to the accompanying drawing, forming a part thereof.

Figure 1 is a front perspective view of the hot air furnace, showing my new design; and

Figure 2 is an enlarged fragmentary elevational view of the grill pattern.

The opposite side of the hot air furnace is like that shown on Figure 1, and the rear walls are substantially plain.

The grill is shown only on part of the two panels in Figure 1. It is to be understood that the grill extends throughout said panels.

I claim:

The ornamental design for a hot air furnace, as shown and described.

RAYMOND R. DUPLER.
